UNITED STATES PATENT OFFICE.

GUSTAVUS A. ECKMAN, OF CHICAGO, ILLINOIS.

MOUNT FOR ELECTRIC FITTINGS.

1,113,762.

Specification of Letters Patent.

Patented Oct. 13, 1914.

Application filed January 30, 1914. Serial No. 815,350.

To all whom it may concern:

Be it known that I, GUSTAVUS A. ECKMAN, a citizen of the United States, residing at Chicago, in the county of Cook and State of Illinois, have invented certain new and useful Improvements in Mounts for Electric Fittings, of which the following is a specification.

One of the objects of my invention is to provide a mount for electric fittings, such as switches, or the like, which will permit the location of the switch to be adjusted in relation to a fixed support, so as conveniently to bring the front surface or face of the switch within the plane or proximate plane of the finished structure, such as the plastering or the trim of a building.

It is now the practice, in placing circuit controlling switches in a building under construction, to first locate the boxes, within which such switches are to be contained and secure them to suitable supports within the building wall at selected locations before the plastering has been done and before the trim is applied. It is very difficult, if not an impossible matter, to invariably locate the switch boxes so that when the plastering has been applied that the face of the switch housing when placed will come just flush with the face or ground of the plastering. If the face of the switch projects beyond the plastering, the box, within which it is to be contained, must then be moved back from the front face of the plaster, which is a task involving considerable work and usually attended with very unsatisfactory results. If the switch box be placed back of the plane in which the front face of the plastering is to appear, the switch has heretofore been mounted in the box by building a mount of a plurality of separate spacing washers, or small tubes, through which the switch-securing screws are passed to bring the face of the switch out beyond the face of the box and in the same plane with the surface of the plastering. Either of these expedients that may be adopted is expensive in time and labor; un-uniform and unworkmanlike in results and generally unsatisfactory. In overcoming these difficulties I provide a fitting mount whereby to position the switch in the switch box or other suitable support, at a suitable distance therefrom, to correspond with the front face of the plastering, after the application of the plaster to the wall,

and so arranged as conveniently to vary the location of the switch in small gradations with reference to its presentation to the plaster face.

In carrying my invention into effect, Figure 1 is an exemplification of a plan view of an electric switch mounted within an outlet box of the usual construction. Fig. 2 is a central vertical sectional view. Fig. 3 is an isometric view of the mount.

In all the views the same reference characters are employed to indicate similar parts.

5 is the outlet box having the usual knock-outs 6—6 to provide orifices for the interior conduits carrying the wires that are to be connected to the switch.

7 is a top or cover for the box, secured thereto by means of ears 8 that project from its front surface and which are adapted to be bent over into contact with the top, or cover, after the latter has been placed in position, as usual with such structures. The cover 7 is provided with inwardly projecting flanges 9—9, having suitable screw threaded perforations, or holes, to receive the attaching screws 10—10. The switch 11 is provided with projecting ears 12—12 through which the attaching screws 10 pass.

15 The switch box 5 is secured to a suitable portion of the wall structure, such as 13, upon the face of which the plaster 14 is to be applied. The box 5 is preferably placed in such location, with reference to the permanent structure 13, that the front surface of the top 7 will come just about flush with the front surface of the structure 13, so that the switch may be applied to the switch box and leave sufficient room at the back portion of the box for admission of the wires that are to come through the conduits that are connected therewith.

20 The mount 15, of which there are two to be used with each switch, consists of a U-shaped portion 16 and terminal base portions 17 and 18 that are flattened so as to occupy substantially the same plane. The U-shaped central portion 16, is slotted at intervals, as at 19, to provide between the slots abutment portions 20. Preferably the slots do not extend to the base portions 17 and 18 but leave an unbroken longitudinal portion 21 for the purpose of strengthening the base portions 17 and 18. The slots 19 are, preferably, in width, equal to the thickness of the flange portion 9 of the top 7 so

that said flange can be conveniently introduced in either of the slots 19 when the mount is being placed in position for support of the switch.

- 5 In applying the device the attaching screws 10 are first passed through the ears 12-12 of the switch 11, after which the mount 15 is placed in the box so that the flange 9 will pass into a selected slot 19, of 10 the mount, to permit the front face of the switch 11 to come substantially flush with the ground or front face of the plastering 14. The attaching screw 10 is then passed into 15 the threaded orifice in the flange 9 and screwed on until the switch 11 is firmly held in contact with the mount, a portion of which intervenes between the switch and the flange 9 of the switch box cover. The extended portion of the screw 10, passes into 20 the box and the unnecessary portion of the mount 15 is also contained within the box, but these portions are out of the way and do not interfere with the usual contents of the box. It will thus be noted that the location 25 of the switch, with reference to its projection from the box relative to the face of the plastering may be adjusted by placing the flange 9, of the cover 7, in any one of the slots 19 and tightening the screw 10.
- 30 In practice each switch or box may be furnished with a pair of mounts, by means of which the front face of the switch may be adjusted in any selected position, with reference to its distance from the face of the 35 box or cover, and should it become necessary, subsequently, to move the switch and to place it in a new position, it can conveniently be done by placing the flange 9, of the cover, in a different slot, of the mount and should 40 the box 5 be initially placed in an angular position, with reference to the front face of the plaster, the front of the switch may be brought into the proper plane by selecting

the proper slots 19-19 within which to place the respective flanges 9-9 of the box 45 cover.

Having described my invention, what I claim with a view and desire to secure by Letters Patent of the United States is:—

1. The combination with an outlet box, 50 having an opening in its front face, of inwardly projecting flanges thereon, having screw receiving openings, a switch, ears projecting therefrom having attachment screw openings therein, the screw openings in the 55 flanges being in alinement with the attachment screw openings in the switch ears, spacer members adapted to abut against the switch ears and transversely slotted for engagement with the flanges and attachment 60 screws passing through the switch ears and into the flanges for clamping said parts together.

2. The combination with an outlet box having an opening in its front face, of inwardly projecting flanges thereon having tapped screw receiving openings, a switch, ears projecting therefrom having attachment screw openings therein, the screw openings in the flanges being in alinement with 70 the attachment screw openings in the switch ears, attachment screws taking through said switch ears and into the tapped openings in the flanges, spacer members adapted to abut at their outer ends against said ears and U-shaped off-set portions on said spacer member passing around said screws, said off-set portions having a plurality of transverse 75 slots therein for adjustable engagement with said flanges.

In testimony whereof I hereunto set my hand in the presence of two witnesses.

GUSTAVUS A. ECKMAN.

In the presence of—
STANLEY W. COOK,
MARY F. ALLEN.
